N. J., a corporation of New Jersey

Original application May 8, 1931, Serial No.
536,031. Divided and this application September
20, 1935, Serial No. 41,467

9 Claims. (Cl. 123—179)

This invention relates to starting mechanism for internal combustion engines, and more particularly to engine starters of the inertia type.

An object of the present invention is to provide 5 a novel means for operatively connecting a starter of the foregoing type to the engine, whereby energy which has been stored in the inertia member of the starter is rendered effective to start the engine.

10 Another object of the invention is to provide in an inertia starter embodying manually operable means for energizing the inertia element, novel engine-engaging means so disposed and inter-related with said energizing means as to permit 15 operation of both through the same agency.

A further object of the invention is to provide in a unitary structure, inter-related means for selectively cranking the engine by transmitting thereto energy previously stored in an inertia element 20 of said structure, or by direct manual operation of an engine-engaging member.

A further object is to provide an engine starter of the foregoing type embodying a novel construction possessing practical merit and insuring 25 efficiency and reliability in operation.

These and other objects will become apparent upon inspection of the following specification and the accompanying drawing, wherein is illustrated the preferred embodiment of the invention. It is 30 to be expressly understood, however, that the drawing is intended merely to serve as an illustration of one mode of embodying the invention in a practical form and is not designed as a definition of the limits of the invention, reference being had for this purpose to the appended 35 claims.

In the drawing,

Fig. 1 is a central vertical section of a device embodying the invention; and

40 Fig. 2 is a transverse sectional view along the line 2—2 of Fig. 1.

Referring particularly to Fig. 1, the invention is therein shown embodied in a housing comprising two sections 5 and 6, the former being adapted 45 to be secured to an extension 7 of the crankcase of an internal combustion engine, the casing 5 being provided for this purpose with a flange 8 having suitable openings adapted to receive bolts 9 for mounting the starter in operative position 50 with respect to the crankshaft 10, or other rotatable member of the engine operatively connected to such crankshaft.

Suitable means are provided for attaching the section 5 to the section 6, such means comprising, 55 as shown, a plurality of bolts 12 adapted to secure

together the flanges 13 and 14 provided on the sections 5 and 6 respectively. The section 6 is further provided with an outwardly extending boss or hub 131 serving to rotatably support a 5 manually operable shaft 128, and within the recessed end 132 thereof there is received an extension 133 of shaft 128, said extension 133 being drivably connected, through suitable speed multiplying mechanism to be described, to a flywheel 21 of suitable mass and weight to constitute an 10 inertia member in which energy may be stored for subsequent transmission to the engine member 10.

The means employed for drivably connecting the hand cranking means just described to the 15 flywheel 21, preferably comprises a system of gearing including a planetary gear assembly associated with the shaft 133 and operable to transmit the rotary movement of said shaft to a second set of gears which are in turn drivably associated 20 with the flywheel. The planetary gearing preferably comprises a plurality of planet gears 32, each of which is rotatably mounted on a bolt 33 threadedly secured to a recessed plate or driving barrel 142 for rotary movement therewith, the 25 barrel 142 having a centrally disposed hub 146, the inner circumferential surface of which is drivably connected to the end of shaft 133, suitable key means 140 being provided for this purpose. The bolts 33 are in turn adapted to be held 30 in proper spaced relation to the barrel 142 by the provision of suitable collars 38 interposed between the bolt heads 39 and the spacer sleeves 40, the latter being adapted to rotatably receive the bearing members 41 on which the gears 32 are 35 mounted.

The planetary assembly further comprises the provision of an internally toothed annular gear 42 which is preferably secured to the casing 5 by means of bolts, dowel pins 43 being also provided 40 to aid in properly positioning the gear 42. The annulus gear 42 therefore constitutes a reaction gear about which the planets 32 travel while rotating around a centrally disposed sun gear 150 with which they mesh. Sun gear 150 is an extension 45 of the hub of a gear 151 rotatable relatively to sleeve 137, the relative rotation being facilitated by provision of bearings 152.

The means for drivably connecting gear 151 with the flywheel 21 preferably includes a gear 50 53 and a pair of pinions 51 and 80, the former being integral with the hub 52 of gear 53 and in mesh with gear 151, and the pinion 80 being in mesh with gear 53, and integral with a shaft 59 rotatably supported, with the assistance of ball 55

bearings 60 and 61, in an annular plate 62 having a flange 63 provided with apertures through which pass screws 64 adapted to threadedly engage correspondingly threaded openings in the dividing wall 56. The member 59 is flanged at its inner end as indicated at 65 with splines adapted to engage alternate members of an annular disc clutch assembly 66, the intermediate members of which are similarly splined at their inner circumferential edges to the hub 67 extending axially forward of the flywheel 21. A spacer sleeve 69 is preferably interposed between the hub 67 of the flywheel and the member 59 of the clutch assembly to permit relative rotation therebetween, the said spacer sleeve also extending forward to permit relative rotation of the member 59 and the centrally disposed shaft or rod 72 which, in cooperation with a spring 43 provided in the recess 14 of the flywheel, maintains the desired frictional pressure on the friction surfaces of the clutch assembly through the pressure of the spring 43 against head 73 of rod 72, suitable tension adjusting means being provided, as shown at 76, where such means takes the form of a collar surrounding the rod 72 and rotatable relatively thereto through the instrumentality of the ball bearing 77, a nut 78 being provided to maintain the collar 76 in adjusted position on the shaft 72. Surrounding extension 133 is a compression spring 135, abutting at one end the shoulder 136 of shaft 133 and at the other end the sleeve 137, functions to normally maintain the meshing member 124 in the position shown in Fig. 1, the spring cooperating to this result with the nut 138 threaded to the end of the shaft 133 and abutting the end surface of the hub of meshing member 124. The latter is in turn secured for rotation with the shaft 133 by the provision of suitable splines 140 and is in turn adapted to rotate the barrel 142 through a suitable driving connection, which indicated at 144, takes the form of radially disposed splines or teeth extending from the member 124 into engagement with corresponding splines or teeth on the end surface of the hub 146 of the member 142. The said hub 146 is further provided with circumferential splines 147 adapted to engage corresponding splines on the inner circumferential surface of the meshing member 123.

The meshing member 123 in the embodiment now being described has associated therewith novel actuating means comprising preferably a meshing shaft 160 to the inner end of which is secured a crank arm 161 having a pin 162 engageable with the circumferential groove 164 of the meshing member 123, the outer end of the pin being provided with a similar crank arm 165, to which is attached a handle 166 and pin 167, constituting an anchoring post for one end of a torsion spring 168, the other end being suitably secured by suitable means 169 to the meshing shaft 160. As best viewed in Fig. 2, a pin 170 formed on the crank arm 165 is adapted to engage a pawl 171 pivoted to the casing and having a tooth 172 normally urged by spring 173 into engagement with a notched recess provided in shaft 160.

Having thus enumerated the parts entering into the embodiment shown in Figs. 1 and 2, it will be evident that the operation thereof is as follows:

When it is desired to crank the engine by the indirect method, the shaft 128 is rotated to store the necessary energy in the inertia member, the flywheel driving connection including an inner

meshing jaw 124, splines 144, spider 142, planet gears 32, gears 150 and 151. When the required amount of energy has thus been stored in the flywheel, the operator turns the crank 165 and thereby causes pin 170 to engage the cam surface 174 of pawl 171, to retract the tooth 172 from shaft 160, thereby permitting torsion spring 168 to whip the outer driving jaw 123 (which has meanwhile been rotating with the spider 142) into a suddenly executed meshing engagement with the engine jaw. This snap action unwinds the spring 168, so that the engine, on starting under its own power, will operate to demesh the starter jaw 123, and at the same time return shaft 160 in locking relation to tooth 172, whereupon spring 173 is effective to hold the parts in non-meshing position until the next starting operation.

When it is desired to crank the engine by direct action, the member 128 is caused to rotate and at the same time move axially forward, thereby compressing spring 135 and moving the inner meshing member 124 into engagement with the engine member 175. Thereupon the engine may be turned over by the direct action of the shaft 128, the connection for the flywheel being broken by the withdrawal of member 124 and the splines 144 from engagement with the hub 146 of spider 142. Upon starting of the engine under its own power, the spring 135 is effective to return the member 124 to the position shown in Fig. 1 whereupon the latter will come to rest assuming cessation of the driving action imparted to the shaft 128.

There is thus disclosed a novel engine starting mechanism of such construction to permit cranking the engine either by direct cranking action or through the intermediary of an inertia member.

It is to be understood that various other changes may be made in the construction, arrangement and inter-relation of the parts constituting the invention without departing from the spirit thereof, the extent of the permissible variations being ascertainable by reference to the appended claims. This application is a division of my application No. 536,031, filed May 8, 1931.

What is claimed:

1. In an inertia starter for internal combustion engines, in combination with an inertia element, a manually operable meshing member, operatively connected with said inertia element to be driven thereby, an engine member, a manually operable shaft for energizing the inertia element of the starter to store therein sufficient energy for cranking purposes, a second meshing member extending through said first named meshing member and movable axially to engage and crank said engine member and means (including said second-named meshing member as an essential part thereof) for operatively connecting said manually operable shaft with said inertia element.

2. In an engine starting mechanism of the type embodying an engine member and a flywheel in which energy is stored for subsequent transmission to said engine member the combination with said flywheel and engine member of torque multiplying connections therebetween including an engine engaging member normally in driving connection with said flywheel, and means for breaking said driving connection and by the same action engaging and rotating said engine member by direct torque transmission thereto, said last named means including a cranking shaft for energizing said flywheel to store therein suf-

ficient energy to crank said engine member by transmitting a multiplied cranking torque thereto.

3. In an engine starting mechanism of the 5 type embodying an engine member and a flywheel in which energy may be stored for subsequent transmission to said engine member, the combination with said flywheel and engine member of torque multiplying connections therebetween including an engine engaging member for rotating

10 said engine member by direct torque transmission thereto, and a second engine engaging member rotatable with said flywheel to crank said engine member by transmitting a multiplied cranking 15 torque thereto, said engine engaging members being disposed in coaxial relation with the axis of said engine member, and means for energizing said flywheel, said energizing means including said first named engine engaging member as an 20 essential part thereof.

4. In combination with an engine member, a 25 pair of driving members having a common axis of rotation, means engageable with one of said driving members to cause longitudinal movement thereof into engagement with said engine member and to cause rotary movement thereof to crank said engine, and means disposed at an 30 angle to said last named means for moving the other of said driving members into engagement with said engine member and means (including said first named driving member as an essential part thereof) for rotating said second named driving member.

5. In combination with an engine member, a 35 meshing member adapted to remain out of mesh with said engine member until after storage of sufficient kinetic energy, an inertia element, means for energizing the inertia element to store in said element sufficient energy to crank said 40 engine member upon movement of said meshing member into engagement therewith, a second meshing member movable axially to engage and crank said engine member and means for drivably connecting said inertia element with said 45 second named meshing member.

6. In combination with an engine member, a meshing member adapted to remain out of mesh

with said engine member until after storage of sufficient kinetic energy, an inertia element, means for energizing the inertia element to store in said element sufficient energy to crank said engine member upon movement of said meshing member into engagement therewith, a second meshing member operative to engage and crank said engine member and means for drivably connecting said inertia element with said second named meshing member. 5

7. In an engine starting mechanism, a combination with a flywheel, means including a driving shaft for energizing said flywheel, an engine engaging member normally in position to drivably connect said shaft with said flywheel, and 15 means for moving said engine engaging member from said normal position into engine engaging position to drivably connect said shaft with a member of the engine to be started and at the same time break the operative connection between said shaft and flywheel. 20

8. An engine starting mechanism comprising a pair of driving members having a common axis of rotation, means engageable with one of said driving members to cause longitudinal movement thereof into engagement with a member of the engine to be started and to cause rotary movement thereof to crank said engine, means disposed at an angle to said last named means for moving the other of said driving members 30 into engagement with said engine member, and common manually operable means drivably connected with said driving members for rotating both said driving members. 25

9. In an engine starting mechanism of the type 35 involving an engine member and flywheel in which energy is stored for subsequent transmission to said engine member, the combination with said flywheel and engine member of an element having operative connection with said flywheel 40 when in one position and mechanically free of any driving relation to said flywheel when in a second position, and means for directly cranking the engine through the instrumentality of said element only when said element is in the second 45 named position.

ROMEON M. NARDONE.
